UNITED STATES PATENT OFFICE.

ALLBEN L. YEAROUS, OF EAGLE GROVE, IOWA.

DESIGN FOR A SHOW-STAND.

SPECIFICATION forming part of Design No. 22,569, dated June 27, 1893.

Application filed May 5, 1893. Serial No. 473,149. Term of patent 7 years.

To all whom it may concern:

Be it known that I, ALLBEN L. YEAROUS, a citizen of the United States, residing at Eagle Grove, in the county of Wright and State of Iowa, have invented and produced a new and original Design for Show-Stands, of which the following is a full, clear, and exact specification.

Reference is to be had to the accompanying drawing forming a part of this specification, in which the figure represents in perspective a stand embodying my new design.

The design consists in the novel configuration shown. Thus a post *a* rises from its base *b* and such post is of decreasing size toward the top, and is divided into divisions *a'* which are separated by cylindrical portions *a²*. The

divisions *a'* are circular, and contracted about centrally thereof, the lines tapering downward and upward from about the center to the adjacent cylindrical figures *a²*, as shown. A series of arms *c* radiate from each cylindrical figure *a²*, and the arms of each set are of gradually less length toward the top. Along each arm a series of pendent hook-like figures *d* appear.

I claim—

The design for a show stand, herein shown and described.

ALLBEN L. YEAROUS.
